APPARATUS FOR TREATING CARTONS WITH
MELTED WAXIrwin Kotcher and Morris Kotcher,
Brooklyn, N. Y.

Application January 30, 1937, Serial No. 123,285

4 Claims. (Cl. 91—46)

This invention relates to improvements in apparatus or means for immersing paper cartons or receptacles in melted wax or the like and for cooling the wax coated cartons for the purpose of rendering the cartons impervious to air and liquid.

More particularly the invention is concerned with an apparatus for coating the interior and exterior of paper receptacles such as form the subject matter of our co-pending applications Serial Nos. 115,016 and 115,015 filed respectively December 9, 1936 and entitled "Cartons" respectively.

The present invention together with its objects and advantages will be best understood from a study of the following description taken in connection with the accompanying drawings wherein:—

Figure 1 is a view mostly in section showing our improved apparatus.

Figure 2 is a vertical sectional view through the immersing apparatus.

Figures 3, 4 and 6 are detail views taken substantially on the lines 3—3, 4—4, and 6—6 respectively of Figure 1.

Figure 5 is an enlarged detail view taken substantially on the line 5—5 of Figure 2 and

Figure 7 is a detail view of a cam disc herein-after more fully referred to.

Referring to the drawings by reference numerals it will be seen that in the preferred embodiment thereof the apparatus comprises an immersing wheel indicated by the reference numeral 1 mounted in a chamber or tank 2, the walls of which are suitably insulated as shown in Figure 2 and wherein is a bath 3 of melted wax or the like.

The immersing wheel 1 is fast on a shaft 4 journaled in suitable bearings 5 provided therefor in opposed walls of the chamber or tank 2 as clearly shown in Figure 1. The said wheel 1 includes a pair of spaced plates or discs 6 which at their peripheries are connected together by a circular series of radially extending carton receiving pockets or cages 7.

Each of the pockets 7 is formed preferably of wire consisting of a pair of opposed U-shaped members which at their open ends are suitably secured to the peripheries of the discs 6 by being welded or otherwise secured thereto, and intermediate U-shaped members connected with each other and with the first mentioned members by cross pieces, as shown. The bottoms of the pockets are formed by wire rods or the like bridging the space between the discs and respectively

welded or otherwise secured at their respective opposite ends to the peripheral edges of the discs.

While we have described somewhat in detail the structure of the pockets 7 it is to be understood that any suitable pocket structure may be resorted to, it being essential only that the pockets be of cage-like formation and opened at their respective opposite sides to permit insertion of a carton into each pocket from one side thereof and the ejection of the carton from a pocket from the opposite side thereof.

This cage-like form of pocket will permit the wax to reach all portions of the carton, both interiorly and exteriorly.

Leading into one side of the chamber or tank 2 is one end of a platform 9 that is in line with one end of an endless conveyor 10 which leads from the carton making machine or other source of supply and which carries the cartons to the platform 9 on to which the cartons successively pass from the conveyor 10 to be successively forced into the successive pockets 7 of the wheel 1.

For ejecting or forcing the immersed cartons successively from the pockets 7 there is slidably mounted in one wall of the tank or chamber 2 a plunger 11, and leading from the tank or chamber 2 at the side thereof opposite to the plunger 11 is a platform 12 on to which the ejected and wax coated cartons pass one at a time as will be clear from a study of Figure 5.

Leading from the platform 12 is an inclined chute 13 and at the junction of the upper end of the chute 13 and the platform 12 there is provided a raised portion 14 which serves to trip the successive cartons 8 to upset them as they pass from the platform 12 on to the chute 13 so as to be delivered by the chute 13 in an inverted position on to an endless conveyor 15. At the lower end thereof the chute 13 is provided with a perpendicular apron 13a and also with an end 13b that serves to position the cartons perpendicularly on the conveyor 15 through the medium of which conveyor the cartons are carried through a cooling chamber 16.

The conveyor 16 consists of an endless belt 15a trained over suitable rollers 15b and the conveyor is driven from any suitable source of power.

Arranged in the cooling chamber 16 is a suitable substantially rectangular skeleton frame structure 17 in which is mounted a coil 18 that extends above and below the conveyor and at opposite sides of the conveyor to insure a thorough and practically immediate cooling of the wax

adhering to the walls, internally and exteriorly of the cartons.

To provide for a forced draft of cold air about the carton thereby insuring a quick cooling of the hot melted wax there are provided in the chamber at the top and bottom thereof suitably mounted fans 19 driven by electric motors 20 as shown in Figure 1.

From the chamber 16 the wax treated cartons 10 are carried to the point remote from the chamber 16 where they are filled with milk or the like.

To guard against the cartons slipping out of the pockets 7 from either side thereof there are provided at opposite sides of the wheel 1 substantially circular guide rails 22, 23 and the guide rail 23 at one side of the platform 12 has a suitable end 23a provided to assist in setting the cartons upright as they are forced from the pockets 7 on to the platform 12.

20 There is also suitably provided a power shaft 24. This shaft is equipped with a cam disc 25 provided with a cam groove 26.

Mounted on one side of the tank or chamber 2 is a bracket 27 to which is pivoted as at 28 one end of a lever 29 the upper end of which has a lost motion connection 30 with the shank of the plunger 11. Adjacent its pivoted end the lever 29 is provided with a laterally extending pin or roller 31 which works in the cam groove 26 in a manner to cause a rocking movement of the lever 29 for projecting and retracting the plunger 11 in timed relation to the wheel 1 so that each time a carton filled pocket 7 passes into position aligning with the plunger 11 the plunger will be forced to the full line position shown in Figure 1 for ejecting the carton from the pocket and positioning the carton on to the platform 12.

40 Adjacent the end thereof connected with the plunger 11, lever 29 is equipped with a dog 32, clockwise movement of which is limited by a suitably provided pin 33.

The dog 32 is cooperable with a ratchet wheel 34 provided on the roller shaft 35 of the conveyor 10, which shaft 35 is journaled in suitable brackets 36 extending from a side wall of the tank or chamber 2 as shown.

50 It will thus be seen that each time the lever 29 moves to the dotted line position shown in Figure 1, dog 32 will engage a tooth of the ratchet wheel 34 so that as the lever 29 moves from the dotted line position to the full line position shown in Figure 1 for ejecting a wax coated carton conveyor 10 will be motivated for transferring a carton therefrom on to the platform 9 with the result that the forwardmost carton on the platform 9 will be forced into an empty pocket 7 that is in alignment with the inner end of the platform 9.

55 For imparting intermittent motion to the wheel 1 in timed relation to the operation of the plunger 11 and the conveyor 10 there is provided on the shaft 4 a disc 37. The wheel or disc 37 is provided in the periphery thereof with a circular series of notches 38 as shown in Figure 3 and provided on the shaft 24 is a disc 39 that is equipped with an eccentrically located pin 40 cooperable with the notches 38 for transmitting rotative movement of the shaft 24 to the shaft 4 for rotating the shaft 4 and the wheel 1 associated therewith step by step for successively bringing 70 the pockets 7 in alignment with the platform 9 and the plunger 11 whereby as a coated carton is ejected from a pocket a carton from the source of supply is being positioned within an empty pocket 7.

75 To preclude pre-rotation to the shaft 4 and

also to prevent retrograde movement of the wheel 1 there is suitably mounted on an adjacent wall of the tank or chamber 2 a spring dog 41 which engages the notches 38 in the disc 37 in a manner shown in Figure 3 so as to have bearing engagement on the periphery of the disc 37 in a manner to offer resistance to the rotation of the shaft 4 and wheel 1 associated with the shaft.

From the description of the invention thus far, it will be apparent that in operation intermittent motion is imparted to the wheel 1, the feed conveyor 10, and the plunger 11 to the end that as an empty pocket 7 moves into alignment with the platform 9 the wheel 1 comes to rest while the conveyor 10 is set into operation to feed a 15 carton from the conveyor 10 on to the platform 9 and also to feed the forwardmost carton on the platform 9 into the empty pocket 7 aligning with the platform while at the same time plunger 11 moves inwardly to engage a coated carton in 20 that pocket 7 in alignment with the plunger 11 so that said coated carton will be forced from the said pocket on to the platform 12 forcing from the platform 12 the previously deposited coated carton, which latter, in an inverted position is 25 directed by the chute 13 on to the conveyor 15 to subsequently pass with the conveyor 15 through the cooling chamber 16 for subjecting the hot coating exteriorly and interiorly of the carton to a relatively low temperature for cooling and 30 hardening the wax coating of the carton as it passes through the chamber 16.

The operation described is controlled through the medium of the cam disc 25 and the roller 31 carried by the lever 29 and operating in the cam groove 26. Thus it will be further appreciated that after each operation of ejecting a coated carton from a pocket 7 on to the platform 12 lever 29 moves from the full line position shown in Figure 3 to the dotted line position shown therein for engaging the dog 32 with the ratchet wheel 34 so that as the roller 31 comes into the position within the cam groove 26 shown in Figure 7 lever 29 will be again caused to move from the dotted line position shown in Figure 3 to the full line position shown therein so that the operation of placing a carton into an empty pocket 7 and the ejecting of a coated carton from the pocket 7 on to the platform 12 is repeated.

50 It will also be appreciated that the timing of the operations may be as found desirable to the end that a number of cartons may be immersed with wax and subsequently fed through the cooling chamber within a minimum amount of time.

55 For maintaining the temperature of the wax bath within the chamber 1 at a predetermined degree there is provided at the bottom of the tank or chamber 2 a coil 42 through which live steam or other heat medium may be caused to circulate, a supply pipe for the coil 42 being shown in Figure 2 and indicated by the reference numeral 43. Pipe 43 is provided with a suitable valve 44 that is controlled by a thermostat 45 which is set to operate the valve 44 and in a pre-determined temperature degree.

Also that the operator may readily ascertain the temperature of the melted wax within the tank or chamber 2 there is suitably provided a thermometer 46 that is electrically connected 70 with a suitable indicator (not shown) which may be located at a point convenient to the operator.

An electric motor or the like may be provided for driving the shaft 24 and the motor in the contemplation of the invention is controlled by 75

a suitable switch 47 including an operative arm 48 that is suitably connected with the stem of a float 49 whereby the switch 47 is opened or closed in response to a rise or drop of the level of the 5 wax bath 3.

Also in accordance with the present invention there is suitably mounted in the upper portion of the tank or chamber 2 a fixed tray 50 that is adapted to receive blocks of wax placed therein 10 through a suitable opening provided in the wall of the tank or chamber 2 and for which opening there is provided a hinged door 51.

Tray 50 is provided with a false wire bottom 52 beneath which is positioned an electrical heat- 15 ing unit 53.

The bottom of the tray 51 is inclined as at 54 and from the bottom 54 leads a feed pipe 55 through which the melted wax flows into the tank from the tray 50. For controlling the flow 20 of wax through the discharge 55 there is provided a valve 56 having an operating stem that extends through a suitable opening provided therefor in the wall of the tank or chamber 2 and is equipped at its outer end with a hand 25 wheel or the like 57 through the medium of which the valve 56 may be operated from without the tank or chamber 2.

Also, for draining the tank or chamber 2 there is provided at the bottom of the tank or chamber 30 a suitable drain valve 58 and in this connection it will be noted that the bottom of the tank or chamber 2 is suitably sloped or inclined toward the valve equipped end thereof.

It is thought that a clear understanding of the 35 construction, utility and advantages of an apparatus of this character will be had without a more detailed description, though attention is called to the fact that when the opening is in the top of a carton, the cartons are placed in the 40 pockets upside down so that as a carton enters the wax, the wax will flow into the carton and this will continue until the carton is full. Then when the carton leaves the wax, it is turned into an inverted position again, so that the wax will 45 drain through the opening of the carton and by the time the carton reaches the ejecting position, all surplus wax will have drained therefrom.

Having thus described the invention what is claimed as new is:—

1. A carton coating device comprising a receptacle having coating material in its lower part, a vertically arranged wheel rotatably arranged in the receptacle and extending into the material, radially extending cage-like pockets on the periphery of the wheel, the sides of each pocket being open, said pockets being fully immersed in the material when that part of the wheel carrying the pockets enters the material, feeding means for placing a carton in each pocket when the 50 pocket reaches the top of the wheel, through one open side of the pocket, a plunger, means for rotating the wheel in a step by step manner and means associated with the rotating means for operating the feeding means and the plunger 55 while the wheel is stationary for ejecting a coated carton from the opposite side of each pocket just before the pocket reaches receiving position.

2. A carton coating device comprising a recep-

tacle having coating material in its lower part, a vertically arranged wheel rotatably arranged in the receptacle and extending into the material, radially extending cage-like pockets on the periphery of the wheel, the sides of each pocket being open, feeding means for placing a carton in each pocket when the pocket reaches the top of the wheel, through one open side of the pocket, a second means for ejecting a coated carton from the opposite side of each pocket just before the 10 pocket reaches receiving position, means for rotating the wheel in a step by step manner, and means for simultaneously operating the feeding means and the ejecting means while the wheel is stationary. 15

3. A carton treating machine comprising a tank having coating material in its lower part, a vertically arranged wheel rotatably supported in the tank and having a part located in the material, radially arranged cage-like pockets 20 connected with the periphery of the wheel, each pocket having an entrance opening at one side of the wheel and a discharge opening at the opposite side thereof, feeding means entering the tank for placing a carton in a pocket when the 25 pocket is at the top of the wheel, an ejector entering the tank slightly in advance of the feeding means for ejecting a treated carton from a pocket just before the pocket reaches the feeding position, said ejector forcing a carton through 30 the discharge opening, said tank having an opening therein, a platform extending inwardly from the bottom wall of the opening for receiving the cartons passing from the discharge openings, an inclined chute leading from the opening in the 35 tank, means for inverting a carton as they pass through the chute, a cooling chamber, and a conveyor receiving the cartons from the chute and passing them through the cooling chamber.

4. A carton coating machine comprising a tank 40 having coating material in its lower part, a vertically arranged wheel rotatably supported in the tank and having a portion located in the material, radially arranged cage-like pockets connected with the periphery of the wheel, each pocket 45 having a receiving opening at one side of the wheel and a discharge opening at the opposite side thereof and the tank having a feeding opening at one side thereof and a discharge opening at the opposite side thereof, rings in the tank 50 slightly spaced from the sides of the pockets of the wheel for preventing cartons from passing through the receiving and discharge openings of the pockets, one ring having an opening therein for registering with the receiving opening of the tank and the other having an opening therein to register with the discharge opening of the tank, means for ejecting a carton from a pocket when said pocket is opposite the discharge opening of the tank, means for feeding a carton into a pocket through the feeding opening of the tank, such means being at the top of the wheel, means for giving the wheel a step by step rotation, and means for operating the ejector means and the feeding means while the wheel is stationary. 55 60 65
